DESIGN FOR A DRESS

Walter B. Earle, New York, N. Y.

Application February 3, 1937, Serial No. 67,418

Term of patent 3½ years

To all whom it may concern:

Be it known that I, Walter B. Earle, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view of the dress shown in Fig. 1.

I claim:

The ornamental design for a dress substantially as shown.

WALTER B. EARLE.
